11 Claims. (Cl. 179—7.1)

This invention relates to time-zone metering in selector operated telephone installations, that is to say, to arrangements for the emission of current impulses in accordance with the distance between the communicating exchanges and the duration of the connection.

The circuit arrangement in accordance with the invention comprises means for the selection of a zone lead characteristic of the connection, i. e. a lead which is characteristic of the distance between the exchanges and means for transmitting through a selected zone lead a number of metering current impulses determined by the duration of the conversation and the tariff in force and in which the transmitting means is common to a number of conversational circuits and comprises a number of cam discs for different tariffs, each having a plurality of series of cams for different units of conversation and each arranged to actuate a transmitting contact connected to one of the zone leads and control means common to all the cam discs for selectively making only one or another of the series of cams on a disc effective to cause the transmission of impulses through the selected zone lead on rotation of the disc.

The impulses may be transmitted to the subscriber's meter at the beginning of each interval in respect of which they are emitted or they may be stored up for transmission to the subscriber's meter at the end of the connection.

In order that the invention may be properly understood and be more readily carried into effect, two examples in accordance therewith will now be described with reference to the accompanying drawing, in which:

Figure 1 shows an arrangement in which the impulses are transmitted immediately to the subscriber's meter, and

Figure 2 shows a modified arrangement in which the impulses are stored until the end of the connection.

The circuit shown in Figure 1 including a time switch and zone selector individual thereto can be seized by a selector (not shown) through the lines *a*, *b*, *c*, *d* and gives access over the lines *a'*, *b'*, *c'*, *d'* to a repeater for extending the connection. The time switch mechanism has a driving magnet *Dz* for a pair of wipers *dz1* and *dz2*. The zone selector has a driving magnet *Dk* through which a wiper *dk1* can be connected to the various leads *II*—*X* corresponding to the various zones, and which lead to the contacts of a metering current impulse transmitter *ZS* shown beneath the chain line in the drawing. The im-

pulse transmitters can be seized by any one of a number of repeaters.

The illustrated arrangement is designed for the case in which there are two possible tariffs, for example a day-time tariff and a night-time tariff. The zone lead *II* has associated with it two cam discs *N II t* *N II n*. The remaining zone leads have similar pairs of cam discs (not illustrated) associated with them. The cam disc *N II t*, which will be assumed to be effective when the day-time tariff is in force, actuates a contact *n II 1* while the cam disc *N II n*—for the night-time tariff—actuates a similar contact *n II 2*. Each of these discs has two series of cams *Nt1*, *Nt2* and *Nn1*, *Nn2*. The number of cams in each of the series *Nt1* and *Nn1* corresponds to the number of impulses which is to be sent out by the transmitter in respect of a three-minute connection at a time when the day or the night tariff respectively is in force. The number of cams in each of the series *Nt2* and *Nn2* corresponds to the number of impulses appropriate to a one-minute connection. Thus, the cam disc *NIIt* associated with the zone lead *II* and effective when the day tariff is in operation has a series of nine cams *Nt1* (for the three minute charge) and a series of three cams *Nt2* (for the one minute charge), while the corresponding cam disc *NIIn*, which is effective when the night tariff is in operation, has a series of six cams *Nn1* and has a series of two cams *Nn2*. The arrangement of the two series of cams on one cam disc necessitates the provision of a control disc *Nst* which is mounted on the same shaft as the cam discs *NIIt* and *NIIn* and actuates a contact *m* which produces a reversal of potential as a series of cams has wiped past one of the contacts *nII1*, *nII2*. The object of this reversal of potential will become clear later on. On the same shaft there is also a cam disc *Nst* which actuates a double-make contact *st*. This contact is always actuated shortly before the contacts *nII1*, *nII2* are actuated by the cams *Nt1*, *Nn1*.

The metering device operates as follows:

When the circuit has been seized, a circuit is closed through the line *c*, *c'* and the relay *C* is energised. When the subscriber dials, the contact *a* is closed at each current impulse (through means not illustrated) and closes the following circuit for the magnet *Dk* of the zone selector:

+, contact *a*, line *d'*, contact *g1*, slow-acting relay *V*, magnet *Dk*, —.

The wiper *dk1* of the zone selector is thus

stepped on to the zone line corresponding to the current impulse train. For the purpose of simplification, it will be assumed that the zone is fully determined by a single current impulse train. If a number of current impulse trains are required for this purpose, an equivalent number of zone selectors has to be provided for the selection of one of the zone leads II—X. The contact $dk2$ is closed mechanically by the shaft of the zone selector as soon as the wiper $dk1$ leaves its rest position. At the end of the current impulse train, the relay V, after a delay, releases and closes a circuit for the relay G:

+, contacts $dk2$ and v , relay G, —.
15 The relay G responds, locks itself in a circuit closed by closing its contact $g2$ and opens the circuit through the line $d1$ at its contact $g1$. A zone line is thus selected by the wiper $dk1$.

When the called subscriber removes his receiver, the line $b1$ is momentarily connected to the negative side of the battery and the winding I of the relay B is thus energised. A locking circuit is then closed through the contact $b2$ and the winding II of the relay. The response of relay B denotes the beginning of the chargeable period of time.

The contact $b4$ connects the magnet Dz of the time switch in a circuit which is closed every ten seconds by the switch $10''$. On the first closing of the switch $10''$, the magnet Dz is energised and the wipers $dz1$ and $dz2$ are stepped from the normal position on to the contacts 1 , in which position the winding I of the relay Z is energised in a circuit including the contacts $b3$ and $f1$, the wiper $dz1$ and the contact $e4$.

By closing its contact $z1$, the relay Z transmits a metering current impulse through the line d . Such a metering impulse is always emitted on response of the called subscriber, so that the calling subscriber may be charged for using the connecting devices. Closing of the contact $z2$ causes the relay E to be energised in a circuit including the contact $f3$. The relay E holds up after dropping of the relay Z in a circuit including the contacts $w3$ and $e1$. When thrown, the contact $e2$ connects the winding II of the relay Z to the negative pole of the battery through a resistance $Wi3$. The emission of metering current impulses by the transmitter ZS is thus prepared.

50 The contact 2 of the contact bank of the time switch wiped by the wiper $dz1$ is connected through a relay T to the double-make contact st . The centre spring of the contact st is connected to the negative pole of the battery through a resistance $Wi1$ and the right hand spring through a resistance $Wi2$. Shortly before the cams $Nt1$ or $Nn1$ wipe past the current impulse contacts $nIII1$, $nII2$, the contact st is actuated by the highest part $y1$ of the cam disc Nst so that the following circuit is closed for the relay T through the resistance $Wi2$:

+, contacts $b3$, $f1$, wiper $dz1$, contact 2 , relay T, (windings I and II),

65 resistance $Wi1$, —
contact st , —
resistance $Wi2$, —

70 The relay T responds and in closing its contact $t2$ short-circuits its high ohmic winding I so that the corresponding relay of another repeater cannot now respond. The relays T of the various repeaters are conveniently given different response characteristics. When the part $y1$ of the cam disc Nst has run past the contact st , the follow-

ing part $y2$ holds the left hand and the centre springs of the contact st together for as long as the cams $Nt1$ or $Nn1$ act upon the contacts $nIII1$, $nII2$. The relay T thus continues to be energised through the high ohmic resistance $Wi1$ and seizure by another repeater is still prevented. When the contact $t1$ closes, the magnet Dz is energised so that the wipers $dz1$ and $dz2$ are stepped on to the third contact.

Closing of the contact $t2$ causes the relay T to continue to hold up in this position of the time switch. Before the control contact st resumes its normal position and the relay T drops, the winding II of the relay Z which is connected to the negative pole of the battery through the resistance $Wi3$ and the contact $e2$, receives the number of current impulses corresponding to the first three-minute period over the contact $t3$, the wiper $dk1$ of the zone selector and the selected zone lead. The contacts $nIII1$ and $nII2$ shown connected to the zone lead II are connected alternatively to the contact m by operation of the switch U which is reversed whenever a change is made from day-time rate to night-time rate and vice versa. In the case illustrated, the metering current impulses corresponding to the three minute charge are emitted by the contact $nII2$ and the contact m is connected to the positive pole of the battery. The following circuit is thus made:

+, contact m , switch U, contact $nII2$, zone lead II, wiper $dk1$, contact $t3$, winding II of relay Z, contact $e2$, resistance $Wi3$, —.

The relay Z transmits the current impulses by means of its contact $z1$. When the one-minute cams $Nn2$, which are arranged on the same cam disc $NII1$ as the three-minute cams $Nn1$, wipe past the transmitting contact $nII2$, the contact m is connected by the cam $Nst1$ to the negative pole of the battery. As the relay Z is also connected to the negative pole through the contact $e2$, no current impulses are emitted.

When the control contact st opens, the relay T drops and the current impulse transmission line is interrupted at contact $t3$. The cam discs of the transmitter ZS rotate once in approximately one second, the wipers of the time switch are stepped through one step every ten seconds. Thus, at the end of two minutes and fifty seconds, the wiper $dz1$ is on the contact 18 through which the following circuit is closed for the relay W:

+, contacts $b3$, $f1$, wiper $dz1$, contact $e3$, relay W, —.

The relay W responds and by means of its contacts $w1$ and $w2$ closes a warning circuit WS through the speech line a , b . In opening, the contact $w3$ opens the circuit for the relay E so that the latter drops and interrupts the circuit for relay W at its contact $e3$, thus opening the warning circuit WS again. The contact $w4$ closes a circuit for the magnet DZ of the time switch so that the wipers are moved on to the contact 19 . In this position, a circuit is closed for the winding II of relay F. The relay F responds and locks itself through its winding I in a circuit including the contacts $c2$ and $f2$. The contact $f1$ then disconnects the wiper $dz1$ and connects the wiper $dz2$. When it released, the relay E connected the winding II of the relay Z to earth by throwing its contact $e2$, so that the relay Z will only respond when the current impulse transmission line is connected to the negative pole of the battery by the contacts m and $nIII1$ or $nII2$.

When the wipers $dz1$ and $dz2$ reach the contact 20 , a circuit for the relay T is prepared

through the contacts *b3*, *f1* and the wiper *d22*. The relay *T* then responds on actuation of the contact *s1* and, by operation of the contact *t1*, resets the time switch into the zero position. The contact *t2* ensures that the relay *T* remains energised until the contact *s1* has been reopened by the cam disc *Nst*. Thereafter, metering current impulses are given every minute until the end of the connection. Thus, when the wiper *d22* arrives at the contacts *6*, *13* and *20*, the relay *T* is energised and steps the time switch one step forward. Metering current impulses are emitted during the energisation of relay *T* as soon as the contact *m* connects the transmission line to the negative pole of the battery:

—, contact *m*, switch *U*, contact *nII1* (or *nII2*), zone lead *II*, wiper *dk1*, contact *t3*, winding *II* of relay *Z*, contact *e2*, +.

The bank contacts may be wiped as many times as desired. It is, of course, clear that switch means could be provided which caused the connecting devices to be released after six minutes or after twelve minutes.

The current impulses for the one-minute charge, which are emitted by means of the cams *Nt2* or *Nn2* and the contacts *nII1* and *nII2*, pass through the same zone lead as the current impulses for the three-minute charge. The only difference is that negative current impulses are emitted instead of positive impulses. This, of course, applies whether day-time or night-time rates are in force so that four different current impulse trains are transmitted over the same zone lead.

In the arrangement illustrated in Figure 1, the contact *z1* of the relay *Z* transmits the metering current impulses immediately through the line *d* to which the calling subscriber's meter may be connected. The subscribers' conversation is therefore not disturbed.

In the arrangement of Figure 2, a switch mechanism is provided which stores the metering current impulses until the end of the conversation and then transmits them through the line *b*. The magnet *Zv* which steps the switch mechanism in one direction is energised at each current impulse on closing of the contact *z3*. When one of the subscribers has replaced his receiver, a contact *s* is closed in a manner not shown so that the relay *X* energises and by means of contact *x1* energises the magnet *Zr*, which steps the switch mechanism in the other direction back into its rest position. At each response, the contact *zr* of the magnet *Zr* interrupts the circuit of the relay *X*. By means of its contact *x2* the relay *X* at each response transmits a metering current impulse through the line *b* to which a meter or a metering impulse repeating relay controlling a meter may be connected. The metering current impulses can also be sent through the line *b* during the conversation if the contact *z3* is arranged in the same way as the contact *x2*. This, however, would mean that the conversation would be interrupted each time for the fraction of a second.

I claim:

1. A telephone installation comprising a plurality of connecting paths, a plurality of repeaters associated individually with said connecting paths and a transmitter arranged for connection to any one of a number of said repeaters and for the emission of a number of metering current impulses, each of said repeaters comprising a plurality of zone leads connected to said transmitter, means for selecting one of said zone

leads, means for connecting a repeater to said transmitter, time switch means for making said connecting means effective at predetermined intervals of time, means for causing said transmitter to transmit a number of metering impulses dependent upon the length of said intervals over said selected zone lead, means for receiving said metering impulses and means for reversing the potential on one side of said receiving means, said transmitter comprising a plurality of cam discs, a plurality of current impulse contacts controlled individually by said cam discs and each associated with a single one of said zone leads, each of said cam discs being provided with a plurality of series of cams, each series comprising a different number of cams and control means for connecting said current impulse contacts to different potentials according as one or another of said series of cams is to actuate the contact in question.

2. A telephone installation comprising a plurality of connecting paths, a plurality of repeaters associated individually with said connecting paths and a transmitter associated with a plurality of said repeaters, said repeater comprising a plurality of zone leads connected to said transmitter, means for selecting one of said zone leads, means for selectively connecting one of said repeaters to said transmitter, time switch means for making said connecting means effective at predetermined intervals of time, means for operating said transmitter for the emission on connection of a repeater to it of a number of metering current impulses dependent upon the length of said intervals, means connected to the selected zone lead for receiving said metering impulses, reversing switch means controlled by said time switch means for connecting said receiving means to different potentials and said transmitter comprising a plurality of cam discs, a plurality of current impulse contacts controlled by different ones of said cam discs and forming groups containing at least one contact, said groups being each associated with a different one of said zone leads, each of said cam discs comprising a plurality of sets of different numbers of cams, a further contact connected to said current impulse contacts for connecting them to different potentials during the actuation of a current impulse contact by one or another of said sets of cams and a further cam disc for controlling said further contact.

3. A telephone installation as claimed in claim 2, in which said reversing switch means are adapted to connect said receiving device selectively to positive and negative potentials and in which said further contact is adapted to connect said current impulse contacts selectively to negative and positive potential.

4. A telephone installation comprising a plurality of connecting paths, a plurality of repeaters associated individually with said connecting paths and a current impulse transmitter associated with a plurality of said repeaters, each of said repeaters comprising a plurality of zone leads connected to said transmitter, means for selecting one of said zone leads, means for selectively connecting said repeaters to said transmitter, time switch means for making said connecting means effective at predetermined intervals of time, means for operating said transmitter for the emission of metering current impulses in trains comprising a number of impulses dependent upon the length of said intervals, means connected to the selected zone lead for receiving

- said impulses and reversing switch means for connecting said receiving means to different potentials, said reversing switch means being controlled by said time switch means and said transmitter comprising a plurality of cam discs, a plurality of current impulse contacts controlled by said cam discs arranged in pairs associated each with a different one of said zone leads, switch means controlled at particular times for connecting one or the other of the current impulse contacts in a pair to its associated zone lead, each of said cam discs being provided with a plurality of sets of different numbers of cams, a further cam disc, a contact controlled by said further cam disc and connected to said last-mentioned switch means whereby to connect said current impulse contacts to different potentials during the action of one or another of said sets of cams.
20. 5. In a telephone installation comprising a plurality of repeaters, the provision of time-zone metering means comprising a plurality of leads corresponding to the various zones, a current impulse transmitter including a number of transmitting contacts equal to the product of the number of zone leads and the number of tariffs and a plurality of actuating cams associated individually with said contacts, means for selectively connecting said repeaters to said transmitter and means for selectively connecting said zone leads to said transmitter through a selected one of said transmitting contacts at predetermined intervals of time, whereby to cause the transmission through the connected zone lead of a number of metering current impulses dependent upon the tariff for the time being in force and the length of said intervals.
6. A telephone installation comprising a plurality of connecting paths, a plurality of zone leads each characteristic of the zone of a connection, means associated with one of said connecting paths for selecting one of said zone leads, a metering impulse repeating relay associated with said connecting path, time switch means associated with said connecting path, a metering impulse transmitter having a plurality of transmitting contacts each connected to one of said zone leads, a plurality of cam discs each controlling one of said transmitting contacts and provided with a plurality of series of cams and control means common to all said transmitting contacts for allowing, on rotation of said cam discs, the transmission of metering impulses by the transmitting contact of a selected zone lead to be effected under the influence of only one of said series of cams on the associated cam disc, each of said connecting paths comprising also switch means controlled by said metering impulse transmitter and by said time switch means at predetermined intervals of time during the connection for connecting said repeating relay of only one connecting path to the selected zone lead at any one time.
7. A telephone installation as claimed in claim 6 comprising also switch means operable to vary the number of current impulses emitted by said transmitter over a selected zone lead.
8. A telephone installation comprising a plurality of zone leads each characteristic of the zone of a connection, a plurality of connecting paths each having associated with it means for selecting one of said zone leads, a metering impulse repeating relay, means for connecting said repeating relay to said selecting means, and a time switch for preparing said connecting means at predetermined intervals of time during the connection, said telephone installation comprising also a metering impulse transmitter having a plurality of transmitting contacts each connected to one of said zone leads, a plurality of cam discs each controlling one of said transmitting contacts and provided with a plurality of series of cams, control means common to all said transmitting contacts for allowing, on rotation of said cam discs, the emission of metering impulses by the transmitting contact of a selected zone lead to be effected under the influence of only one of said series of cams of the associated cam disc and control means for making effective the connecting means of only one connecting path which has been prepared by said time switch before the beginning of the emission of current impulses.
9. A telephone installation as claimed in claim 8 comprising a contact controlled by said repeating means for the immediate repetition of the received metering impulses.
10. A telephone installation as claimed in claim 8 comprising also a storing device controlled by said repeating means for storing the metering impulses emitted by the transmitter during a connection and for transmitting said metering impulses during its restoration into its normal position.
11. A circuit arrangement for time-zone metering in selector operated telephone installations comprising a plurality of conversational circuits, a plurality of zone leads, means for selecting a zone lead characteristic of the connection and means for transmitting through a selected zone lead a number of metering current impulses determined by the duration of the conversation and the tariff in force, said transmitting means being common to a plurality of said conversational circuits and comprising a plurality of transmitting contacts connected to said zone leads and a plurality of sets of cam discs—one set for each zone lead—each set of cam discs comprising one for each different tariff and each cam disc comprising a plurality of series of cams for different units of conversation, and control means common to all said cam discs for selectively making only one or another of said series of cams on a disc effective to actuate one of said transmitting contacts.

MARTIN HEBEL.
